DESIGN FOR A HELICOPTER

Othmar F. Maycen, New York, N. Y.

Application January 28, 1944, Serial No. 112,356

Term of patent 14 years

(Cl. D71—1)

To all whom it may concern:

Be it known that I, Othmar F. Maycen, a citizen of the United States, residing at the Borough and county of Bronx, city and State of New York, have invented a new, original, and ornamental Design for a Helicopter, of which the following is a specification, reference being had to the accompanying drawing, forming part thereof, wherein:

Figure 1 is a top plan view of a helicopter showing my new design;

Figure 2 is a side elevational view of the helicopter; and

Figure 3 is a front elevational view of the helicopter.

I claim:

The ornamental design for a helicopter, substantially as shown.

OTHMAR F. MAYCEN.
